UNITED STATES PATENT OFFICE.

WILLIAM ERASTUS WILLIAMS, OF CHICAGO, ILLINOIS.

STEEL-FELLY WHEEL.

1,367,847.

Specification of Letters Patent.

Patented Feb. 8, 1921.

Application filed January 8, 1920. Serial No. 350,109.

To all whom it may concern:

Be it known that I, WILLIAM ERASTUS WILLIAMS, a citizen of the United States, a resident of Chicago, in the county of Cook and State of Illinois, have invented a new and useful Improvement in Steel-Felly Wheels, of which the following is a specification.

The object of this invention is to provide a wheel having a steel felly and peculiar steel spokes and yet lighter than a wood wheel, quite as strong, and less expensive.

The invention is set forth in the claims.

Reference will be had to the accompanying drawing in which Figure 1 is a front elevation of the wheel.

Fig. 2 is a radial transverse section on a larger scale than Fig. 1, showing one-half of the wheel.

Fig. 3 is a section on line 3—3 of Fig. 2.

Fig. 4 is a section on line 4—4 of Fig. 1.

Fig. 5 is a plan of one of the stampings which is partly finished in the operation of making the spokes.

Fig. 6 is a side, or edge view of the stamping shown in Fig. 5.

Fig. 7 is a view similar to Fig. 6, showing a modified form for the spoke, when the cross section curvature is omitted and the metal allowed to stay in a flat sheet as relates to a cross section of the spokes.

Fig. 8 is a view corresponding to that of Fig. 4, with the flat spokes used as is indicated by Fig. 7.

In the drawing, 1 indicates the ordinary hub of a pleasure car wheel, herein shown as the rear hub. This hub is made of a casting having the front curved surface 2, and ribs 3, which support an annular flange section 4 and a vertical annular flange section 5.

In the outer flange or circumference 4, I provide a series of rectangular cavities 6 in which the ends 7 of the spokes are keyed by a series of keys 8.

The main spoke body sections 9 and 10 are made of a flat strip of metal 11 indicated by Fig. 5.

The flat strip 11 is pierced at 12 and cut asunder at the ends as indicated at 13 and 14, and this flat strip is bent while it is still in the flat as is shown by Fig. 6 and in this bending and piercing operation the spoke is pressed into curved shape as is indicated by 15 in Fig. 4.

The two sides of the strip shown in Fig. 5 are folded over upon themselves, and the

central portion 16, which is still intact, is folded into an oval as indicated by the section 17 in Fig. 3, which is in the middle region of the spoke body. At this region a series of clips 18 are secured, through the medium of the nuts 19, to the body 20 of the brake drum, and the latter is fastened also at the hub, by bolts 21.

In the case of the front wheel, where no brake drum is needed the clips 18 are omitted and the cold shut union 22, as indicated in Fig. 3, is welded or otherwise suitably secured together.

In place of this welding of this cold shut seam 22 I may clamp on a ring or I may rivet the two sides of the spoke body at this point to each other and get the corresponding bracing results desired.

The spoke ends 10 turn over at 23, (see Fig. 6) and they are secured in small depressions 24 in the web 25 of the channel section felly.

The ends 23 are secured to the felly by the rivets 26 or are spot welded as desired.

The depressions 24 and side walls 27 take side thrusts of the ends 23 of the spokes, so that not all of the side or skidding strains are necessarily borne by the rivets 26.

The felly of the wheel in this case is made of a channel section having the web 25 and the rear abutment flange 28 and the forward inclined flange 29, which are shown here as being used with a demountable rim shown in dotted lines as 30. This rim has an inclined face 31 that bears on the flange 28 of the felly and has an inclined face 32 which bears on the flange 29 of the front flange 33 of the channel section felly.

A series of clips 34, and bolts 35 clamp the demountable rim 30 to the felly as indicated.

In assembling the wheel I form the spokes in the right shape as desired and then I secure the spokes to the felly as the first step, then I assemble the hub in position underneath the spokes and then I press the hub parallel with its axis, up into its proper relationship, with the spokes entering in this movement. The ends 7 of all the spokes simultaneously entering into the cavities 6 of the hub and when the hub is home I then force in the keys 8, securely fastening the spokes into the hub by the wedging action of the keys.

The keys 8 are made slightly tapered as are the cavities 6, so that when the keys are

pressed home the several ends 7 are very firmly secured in the hub.

After the keys are home I rivet over their inner ends, which prevents their coming out.

By this arrangement of the spokes they are very securely braced into the wheel and adapted to take up the torsional strains of the axle together with the direct side thrust strains involved in the service of the wheel.

What I claim is:—

1. In a wheel of the class described, a metal hub, a metal rim, said rim forming the fixed rim portion and indented outwardly for the spoke section, with a series of spokes made of flat metal and keyed in the hub and with their outer ends turned over and seated in the outward depressions of the rim.
2. In a wheel of the class described, a metal hub and a metal rim in the form of a channel section having the flanges of the channel projecting outwardly, forming the tread portions of the rim, the spoke seats indented outwardly in the web section of the said channel rim and with flat metal spokes suitably fixed to the hub and having their outer ends turned over and seated in depressions in the web of the channel section of the rim and secured therein.
3. In a wheel of the class described, a metal hub, a metal rim, having a series of spokes secured to the hub and to the rim

and the said spokes having their ends turned over in angular form and seated in depressions in the rim and secured therein by riveting.

4. In a wheel of the class described, a channel section rim, a metal hub, flat metal spokes, the said spokes connected together in pairs in the middle body portion of the spokes and connected to the hub and to the rim by having their ends turned over and secured in recesses in both the hub and the rim.

5. The combination with a hub and a rim, of pairs of metal spokes widely separated at both hub and rim and each having its middle portion deflected to the oppositely deflected middle portion of its companion and secured thereto.

6. The combination with a metal hub and rim, of broad flat-metal spokes all in a plane, arranged in pairs widely separated at both hub and rim and having their intermediate portions brought together, and clips rigidly connecting the portions thus brought together.

Signed at Chicago, in the county of Cook and State of Illinois, this nineteenth day of December, 1919.

WILLIAM ERASTUS WILLIAMS.
